CLAIM

The ornamental design for a fishing lure attachment, as shown and described.

DESCRIPTION

FIG. 1 is a perspective view of a fishing lure attachment showing the design;

FIG. 2 is a top view thereof;

FIG. 3 is a front view thereof;

FIG. 4 is a bottom view thereof; and,

FIG. 5 is a side view thereof.

The shading shown in the figures is for illustrative purposes only and does not form any part of the design.
